UNITED STATES PATENT OFFICE.

MATTHEW W. ADAMS, OF OMAHA, NEBRASKA.

CUSPIDOR.

1,116,967.

Specification of Letters Patent. Patented Nov. 10, 1914.

Application filed September 21, 1914. Serial No. 862,696.

To all whom it may concern:

Be it known that I, MATTHEW W. ADAMS, a subject of the King of Hungary, residing at Omaha, in the county of Douglas and 5 State of Nebraska, have invented certain new and useful Improvements in Cuspidors, of which the following is a specification, reference being had therein to the accompanying drawing.

This invention relates to cuspidors and 10 has for its object to provide a device of such class, in a manner as hereinafter set forth, with means to prevent the spilling of the contents of the cuspidor when the cuspidor 15 is tilted or upset.

Further objects of the invention are to 20 provide a cuspidor for the purpose set forth, which is simple in its construction and arrangement, strong, durable, efficient in its use, readily set up, and comparatively inexpensive to manufacture.

With the foregoing and other objects in 25 view the invention consists of a novel construction, combination and arrangement of parts as hereinafter more specifically described and illustrated in the accompanying drawing, wherein is shown an embodiment of the invention, but it is to be understood that changes, variations and modifications 30 can be resorted to which come within the scope of the claims hereunto appended.

The drawing, illustrates in vertical section, a cuspidor in accordance with this invention.

35] Referring to the drawing in detail, 1 denotes a dome-shaped base provided at its top with an annular shouldered flange 2 and further provided with an inwardly extending annular support 3, having a centrally disposed sleeve 4. Formed integral with the flange 2 is a cup-shaped member 5, having a vertically disposed annular collar 6 which is interiorly threaded and further having a central opening 7.

45] The reference character 8 denotes a body portion, which is somewhat globular in contour, and is provided at its top with a vertically disposed neck 9, having a pair of spaced inwardly extending annular flanges 50 10, 11. Formed integral with the neck 9 is a funnel-shaped mouth piece 12 and interposed between the flanges 10, 11, as well as projecting inwardly from the flange 10, is a resilient gasket 13 which constitutes a valve 55 seat. The flange 10 is of greater width than the flange 11. The lower end of the body

portion 8 is formed with a depending annular collar 14, which is interiorly threaded and has threaded engagement with the flange 2, as well as abuts against the shoulder of 60 said flange 2. The body portion 8, at its bottom, is furthermore provided with an inwardly extending flange 15, which opposes the flange 16, the latter being a part of the cup-shaped member 5, and is not only 65 formed integral with the member 5, but also with the flange 2. Interposed between the flanges 15, 16 is a resilient gasket 17.

Mounted upon the member 5 and having threaded engagement with the collar 6, is a 70 vertically disposed sleeve 18 and arranged therein, at the bottom thereof, and resting upon the member 5, is a resilient gasket 19, against which bears an apertured disk 20. Bending down through the sleeve 18, disk 75 20, gasket 19, and opening 7 is a valve stem 21, which is provided with a collar 22, and interposed between said collar 22 and disk 20, as well as surrounding the stem 21, is a coil spring 23, which normally maintains 80 the stem 21 projected upward. The lower end of the stem 21 is provided with a hook 24, and the upper end thereof, which projects above the sleeve 18, has secured thereto, as at 25, a cone-shaped valve 26, which is 85 adapted to engage the seat 13, to close the body portion 8. The spring 23, acts to normally maintain the valve 26 in engagement with the seat 13.

Mounted upon the top of the sleeve 18, is 90 a gasket 27, which is maintained in position by a cap 28 having threaded engagement with the sleeve 18. The stem 21 projects through the gasket 27 and cap 28.

Secured to the support 3, as well as depending therefrom, is a hanger 29, having a counter-balanced lever 30, pivotally connected therewith as at 31. Depending from one end of the lever 30 is a weight 32 and that end of the lever 30, having the weight 32, is 95 tapered as at 33 for engagement with the hook 24 of the stem 21, whereby the latter is maintained in a lowered position so that the valve 26 will be as indicated in dotted lines. When the cuspidor is tilted or upset, 100 the lever 30 is shifted from engagement with the hook 24 and the spring 23 will shift the stem 21 to bring the valve 26 to engage the seat 13 thereby closing the body portion 8.

What I claim is:—

1. A cuspidor comprising a base, body portion connected therewith and having a

funnel-shaped mouth piece, said body portion having means to constitute a valve seat, a spring controlled stem arranged in said body portion and capable of projecting into said base and carrying a valve normally engaging said seat, said stem having a hook at its lower end, and a counter-balanced lever suspended in said base and engaging said hook for maintaining the valve in open position until the body portion is tilted or shifted.

2. A cuspidor comprising a base, a body portion connected therewith and having a neck provided with means to constitute a valve seat, a funnel-shaped mouth piece projecting from said neck, a valve, spring con-

trolled means connected with said valve for normally maintaining the valve against its seat to close said body portion, said means including a hook capable of being shifted into said base, and counter-balanced means arranged within said base and capable of engaging said hook for maintaining said valve in open position until the hook is released by the tilting or upsetting of the cuspidor. 20 25

In testimony whereof I affix my signature in the presence of two witnesses.

MATT W. ADAMS.
